US00D903142S

(12) **United States Design Patent** (10) Patent No.: **US D903,142 S**
(45) Date of Patent: ** *Nov. 24, 2020

(54) **PORTION CUP**

(71) Applicant: **RhinoSystems, Inc.**, Brooklyn Heights, OH (US)

(72) Inventors: **Martin R. Hoke**, Lakewood, OH (US); **Robert D. Schilling**, Olmsted Township, OH (US); **Patrick W. Brown**, Auburn, OH (US); **Jeffrey S. Taggart**, McLean, VA (US)

(73) Assignee: **RhinoSystems, Inc.**, Cleveland, OH (US)

(*) Notice: This patent is subject to a terminal disclaimer.

(**) Term: **15 Years**

(21) Appl. No.: **29/571,111**

(22) Filed: **Jul. 14, 2016**

Related U.S. Application Data

(60) Continuation of application No. 29/536,867, filed on Aug. 20, 2015, now Pat. No. Des. 763,463, which is a division of application No. 29/472,367, filed on Nov. 12, 2013, now Pat. No. Des. 739,552, and a continuation-in-part of application No. 29/360,918, filed on May 3, 2010, now Pat. No. Des. 662,217.

CLAIM

The ornamental design for a portion cup, as shown and described.

DESCRIPTION

FIG. 1 is a perspective view of an embodiment looking into the cup;

FIG. 2 is a front plan view thereof;

FIG. 3 is a left side plan view thereof;

FIG. 4 is a back plan view thereof;

FIG. 5 is a right side plan view thereof;

FIG. 6 is a top view looking into the cup;

FIG. 7 is a bottom end view thereof; and,

FIG. 8 is a perspective view thereof.

The broken lines depict portions of the portion cup that form no part of the claimed design; the broken lines and the unshaded surfaces form no part of the claimed design.

1 Claim, 3 Drawing Sheets
